UNITED STATES PATENT OFFICE

167,312

SAVINGS BANK

Elliot Handler, Los Angeles, Calif.

Application December 10, 1951, Serial No. 17,677

Term of patent 3½ years

(Cl. D34—11)

To all whom it may concern:

Be it known that I, Elliot Handler, a citizen of the United States, residing in Los Angeles, county of Los Angeles, State of California, have invented a new, original, and ornamental Design for a Savings Bank, of which the following is a specification, reference being had to the accompanying drawing, forming part thereof.

I claim:

The ornamental design for a savings bank, as shown.

ELLIOT HANDLER.
